UNITED STATES PATENT OFFICE.

LEVETT T. GRANDY, OF DETROIT, MICHIGAN, ASSIGNOR TO C. M. HALL LAMP COMPANY, OF DETROIT, MICHIGAN, A CORPORATION OF MICHIGAN.

FOCUS ADJUSTMENT FOR LAMPS.

1,159,492.

Specification of Letters Patent.

Patented Nov. 9, 1915.

Application filed March 15, 1915. Serial No. 14,603.

To all whom it may concern:

Be it known that I, LEVETT T. GRANDY, a citizen of the United States of America, residing at Detroit, in the county of Wayne and State of Michigan, have invented certain new and useful Improvements in Focus Adjustment for Lamps, of which the following is a specification, reference being had therein to the accompanying drawings.

10 The invention relates to focus adjusting means for headlights and has for its object the obtaining of a simplified construction and one which is easy to manipulate.

In the drawings: Figure 1 is a perspective view of a lamp socket provided with my improved focus adjustment; Fig. 2 is a longitudinal section therethrough; and Fig. 3 is an end elevation.

A is the reflector, preferably of the usual parabolic form and B is the tubular rearward extension for receiving the lamp socket C. This socket C may be of any suitable construction adapted for the detachable engagement therewith of a lamp, such as D, and as shown the lamp is engaged and locked in the socket by means of pins D' engaging slots E having a locking notch F. Any suitable means for resiliently holding the pins D' in the locking notches F may be used, but as shown the electrical contacts G for coöperation with the lamp contacts H are resiliently yieldable.

To provide a ready means for adjusting the lamp longitudinally for focusing, I have provided upon the socket and the tubular holder a notched or serrated member upon the one and a detent upon the other so constructed as to be disengageable by a rocking or lateral movement of the lamp socket in the tube B. As specifically shown the socket C is in the form of a cylinder struck up from a sheet metal blank and having a radially, outwardly and longitudinally extending flange I notched or serrated along its outer edge as indicated at J. The tube B is provided with an outwardly and transversely-extending flange K, which is slotted for the passage of the flange I on the socket, and has a sharp edge L for engaging the serrations. Lateral movement of the socket to permit of disengagement of the serrated flange from the detent flange L is provided by cutting away the opposite portion of the tube B. This permits the socket to be rocked in the tube, but normally it is held

from this movement by resiliently yieldable means. This, as shown, comprises a shoe M, which is connected to the tube B by resilient wire loops N, and normally presses the socket C against the imperforate portion of the tube B.

With the construction as described, the lamp bulb D may be readily engaged or disengaged from the socket C by a longitudinal and rotary movement. In accomplishing this the tension of the resilient yieldable contacts G must be overcome, but inasmuch as the socket C is locked by the serrated flange J engaging the detent L, said socket will be held from displacement. When, however, it is desired to longitudinally adjust the socket, a slight tilting in the tube B will disengage the serrated flange I from the detent, permitting inward or outward longitudinal adjustment.

The device as above described is one which is exceedingly simple to manufacture, while the manipulation both in engaging the lamp bulb and in adjusting for focus is also easily performed.

What I claim as my invention is:—

1. The combination with a lamp socket and a holder therefor, of a longitudinally-extending notched or serrated member upon the one engaging a detent upon the other, and means yieldably holding said serrated member and detent in engagement, permitting of lateral bodily movement of the socket for disengagement.

2. The combination with a lamp socket, of a holder for said socket permitting longitudinal adjustment thereof, and means for locking said socket in different positions of adjustment, disengageable by a lateral bodily movement of the socket.

3. The combination with a lamp socket, of a holder for said socket permitting longitudinal and lateral bodily movement of the socket therein, means for yieldably holding said socket from lateral movement, and means for locking said socket in different positions of longitudinal adjustment while held from lateral movement, said locking means being disengaged by a lateral bodily movement.

4. The combination with a lamp socket, of a tubular holder with which said socket is telescopically engaged, said holder being cut away on one side to permit a lateral movement of the socket, means for resiliently

yieldably holding said socket from lateral movement, and means for locking said socket in different positions of longitudinal adjustment in said holder while held from lateral movement, said means being disengageable by a lateral movement.

5. The combination with a lamp socket having a longitudinally-extending serrated flange thereon, of a holder for said socket

10 longitudinally slotted for the reception of said flange and having a detent for engaging the serrations of said flange, the opposite side of said holder being cut to permit of lateral movement of said socket for disengagement from said detent, and a resiliently pressed means for normally holding said socket in position for locking of said detent.

15 6. The combination with a lamp socket having a longitudinally-extending notched or serrated flange, of a holder for said socket slotted for the passage of said flange, and cut away on the opposite side from said slot to permit of the lateral movement or tilting 20 of said socket, a transversely-extending flange on said holder also cut away for said longitudinal flange and having a detent for engaging the serrations of said longitudinal flange, and a resiliently pressed means for 25 yieldably holding said socket with the serrated flange thereof in locking engagement with said detent.

30 7. The combination with a lamp socket, of a holder in which said socket is longitudinally adjustable, means for locking said socket in different positions of longitudinal adjustment in said holder, said locking means being disengageable by a lateral bodily movement of the socket in said

holder, means for resiliently and yieldably holding said socket from lateral bodily movement, a lamp having a locking engagement with said socket, operable by a longitudinal and rotary movement of the lamp, and means for yieldably opposing the longitudinal movement of said lamp in said socket to hold the same in the locked position.

40 8. The combination with a lamp socket having a longitudinally-extending notched or serrated flange, of a tubular holder for said socket longitudinally slotted for said flange and cut away on the opposite side to permit of a lateral movement of said socket, a transversely-extending flange on said 45 holder slotted for the passage of said longitudinal flange and having a detent for engaging the serrations thereof, a shoe for engaging said socket in the cutaway portion of said holder, and resilient means for connecting said shoe with the imperforate portion of the holder to resist lateral movement of said socket.

50 9. The combination with a lamp socket provided with a radially, outwardly and longitudinally notched flange, of a holder for said socket having a detent engageable with the notches of said flange, and means for yieldably holding said detent in engagement with said notched flange, permitting 55 of a tilting movement of the socket for disengagement.

60 In testimony whereof I affix my signature in presence of two witnesses.

LEVETT T. GRANDY.
